UNITED STATES PATENT OFFICE

CHARLES EMANUEL ALBERTI, OF CHICAGO, ILLINOIS

VISIONOGRAPH RECORD AND METHOD OF MAKING THE SAME

Application filed August 13, 1928, Serial No. 299,408. Renewed October 24, 1930.

My invention relates to visionograph records and methods of making the same, and it consists in the steps hereinafter described and the combinations, constructions, and arrangements herein described and claimed.

An object of my invention is to provide a visionograph record of a type whereby images may be reproduced.

A further object is to provide a visionograph record by means of which the reproduction of images and sound may be reproduced synchronically.

A further object is to provide a method wherein a record may be prepared for reproducing an image and a record prepared for reproducing sound, and in which the production of the two records may be performed synchronically.

A further object is to provide a method whereby a single record or a plurality of records may be produced adapted to reproduce images and sound synchronically.

Other objects and advantages will appear in the following specification, and the novel features of the invention will be particularly pointed out in the appended claims.

My invention is illustrated in the accompanying drawings, forming part of this application, in which

Figure 1 is a diagrammatic view embodying the structure employed in my method for preparing a visionograph record,

Figure 2 is a plan view of a scanning disc,

Figure 3 is a top plan view of a portion of the structure shown in Figure 1,

Figure 4 is a view of a single record prepared to reproduce sound and images,

Figure 5 is a view showing a further modification of the record shown in Figure 4, and

Figure 6 is an enlarged sectional detail view showing a further modification of my record.

In carrying out my invention, I make use of a main shaft 1 having a gear 2 operatively disposed with respect to a gear 3 mounted upon a shaft 4 associated with a motor 5. The shaft 1 is provided with a pair of bevel gears 6 and 7 and a smaller bevel gear 8. Any suitable means may be provided for rotatably mounting the shaft 1.

A scanning disc 9 is secured to the shaft 1 and is provided with a plurality of small openings 10 disposed in a spiral path near the outer edge, as shown in Figure 2. The disc may or may not be provided with lenses.

A platform 11 is positioned in operative relation with respect to the shaft 1, as shown in Figure 1. Turntables 12 and 13 are mounted upon the platform and are operatively connected with shafts 14 and 15, respectively. The shafts 14 and 15 are provided with bevel gears 16 and 17 disposed in operative engagement with the bevel gears 6 and 7, respectively. The bevel gear 8 is operatively connected with a bevel gear 18 associated with a governor 19. The gear 18 is mounted upon a shaft 20 having a movable disc 21 disposed thereon. Suitable frictional means 22 are operatively connected with a rod 23 having an adjusting nut 24 for moving the frictional means 22 toward or away from the disc 21.

Suitable arms 25 and 26 are pivotally mounted at 27 upon the platform 11. Each of the arms is provided with a suitable recorder 28 and 29 of the electromagnetic type. The recorders 28 and 29 are provided with needles 30 and 31, respectively.

A photo-cell 32 is disposed relatively close to the scanning disc 9 and opposite the path of the openings 10. A conductor 33 electrically connects the photo-cell with an amplifier 34, and a conductor 35 connects the amplifier with the recorder 28. A conductor 36 leads from the recorder 28 to a source of current 37. The photo-cell 32 is electrically connected with the source of current 37 by means of a conductor 38.

The recorder 29 is provided with a conductor 39 connected with a source of current 40. A conductor 41 electrically connects a microphone 42. A conductor 43 leads from the microphone 42 to an amplifier 44, the latter being electrically connected with the recorder 29 by means of a conductor 45. A suitable lens 46 is disposed near the scanning disc 9 and upon that side opposite the photo-cell 32. The lens 46 is adapted to focus light rays from an optical image 47.

From the foregoing description of the vari-

ous parts of the device, the operation thereof may be readily understood. The motor 5 rotates the shaft 1 and the scanning disc 9 at a relatively high rate of speed. Rotation of the shaft 1 rotates the shafts 14 and 15 of the turntables 12 and 13. Records 48 and 49 are placed upon the turntables 12 and 13, respectively. During the rotation of the scanning disc, the openings 10 will pass through a plane intersecting the image projected upon the edge of the disc by the lens 46. As the openings pass across the projected image, light will pass through the openings in accordance with the intensity of the light in the cross section of the image. The light passing through the openings falls upon the photo-cell 32 or any suitable means.

Since the light which passes through the openings will vary in accordance with the intensity of the light in the path of the projected image, it will be seen that the light falling upon the photo-cell or any other suitable means will cause a greater or less amount of electricity to flow through the photo-cell. The variation of the current by reason of the photo-cell will cause electrical impulses which result in actuating the needle 30. The movement of the needle will cause undulations to be formed within the groove of the record. The records 48 and 49 rotate at the same speed. This is easily attained by providing gears 6 and 16 of the same ratio as the gears 7 and 17. The ratio between the gears 6 and 16 and 7 and 17 may be changed to attain any desired speed for the records. In referring to Figure 1, it will be seen that sound may be recorded upon the record 49 through the microphone 42. It is thus possible to synchronize the visionograph record 48 and the record 49. The visionograph record 48, see Figure 3, is provided with an opening 50, and the record 49 is provided with an opening 51. The openings permit the two records to be placed in their same relative positions when reproducing as during the process of recording.

In Figure 4 I have shown a record 52 having parallel grooves 53 and 54. One of the grooves comprises the image undulations, and the other groove the sound undulations. Such a record is easily prepared by providing a pair of recorders placed side by side. In Figure 5 I have shown a record divided into two portions 55 and 56. In this record the image undulations may be formed in the face of the portion 56 and the sound undulations in the face of the portion 55.

In Figure 6 I have shown a further modification of a record in which a groove 57 is provided in the bottom of the groove 58. In this form, the image undulations may be formed in the groove 58, and the sound undulations in the groove 57, or vice versa. Such a record is formed by placing one recorder before the other.

While I have defined in detail the preparation of my visionograph record, it will be seen that when once a record has been prepared, an image may be reproduced by reversing the process; that is to say, by placing a prepared record upon the turntable 12. The undulations within the groove of the record imparted to the needle will be changed into electrical impulses by means of a device such as is used in phonograph electric pick ups. The variable electric current thus produced is amplified, and, by the provision of suitable apparatus, such as that used in a television receiver, a source of light will be caused to vary in intensity. The fluctuation of the light caused by the variable flow when looked at through a scanning disc will give to the eye a reproduction of the image. It is of course necessary that the scanning disc and the record revolve at the same ratio of speed as that used during the production of the record. While I have defined specifically the scanning disc 9, it will be understood that various devices may be employed, such as an endless film-like member, and other moving members.

I claim:

1. A device of the type described comprising a rotatable shaft, a disc secured to the shaft and having a plurality of openings arranged in the form of a spiral, a plurality of shafts operatively connected with said rotatable shaft, a turntable carried by each of said plurality of shafts, a record disposed upon each of the turntables, means for projecting an image of a distant scene upon that portion of the disc having the openings therein, the rays of light from said image passing through the openings in the disc when the latter is rotating in substantially a continuous beam, light-sensitive electrically controlled means adapted to vary electric current in proportion to the light passing through the openings, means associated with said light-sensitive electrically controlled means for forming undulations in one of said records, and sound-sensitive means associated with the other of said records for forming undulations therein.

2. A device of the type described comprising a rotatable shaft, a disc secured to the shaft and having a plurality of openings arranged in the form of a spiral, a plurality of shafts operatively connected with said rotatable shaft, a turntable carried by each of said plurality of shafts, a record disposed upon each of the turntables, means for projecting an image of a distant scene upon that portion of the disc having the openings therein, the rays of light from said image passing through the openings in the disc when the latter is rotating in substantially a continuous beam, light-sensitive electrically controlled means adapted to vary electric current in proportion to the light passing through the

openings, means associated with said light-sensitive electrically controlled means for forming undulations in one of said records, sound-sensitive means associated with the other of said records for forming undulations therein, and means operatively connected with said rotatable shaft for attaining a uniform speed.

3. A device of the type described comprising a rotatable shaft, means actuated by said shaft and having a plurality of openings therein, a plurality of shafts operatively connected with said rotatable shaft, a turntable operatively connected with each of said plurality of shafts, means for projecting an image of a distant scene upon that portion of the first-named means having the openings therein, the rays of light from said image passing through the openings in said first-named means when the latter is moving, a record disposed upon each of said turntables, an electrically sensitive recorder associated with each of the records, light-sensitive electrically controlled means adapted to vary electric current in proportion to the light passing through said openings and associated with one of said recorders for forming undulations in one of the records, and sound-sensitive means associated with the other of said recorders for forming undulations in the record associated therewith.

4. A device of the type described comprising a rotatable shaft operatively connected with a power unit, a disc secured to the shaft and having a plurality of openings arranged in the form of a spiral, a pair of shafts having gear connections with said rotatable shaft, a turntable associated with each of said shafts, a record disposed upon each of the turntables, an electrically sensitive recorder associated with each of said records, means for projecting an image of a distant scene upon that portion of said disc provided with the openings, the rays of light from said image passing through the openings in said disc when the latter is moving, light-sensitive electrically controlled means adapted to vary electric current in proportion to the light passing through said openings and associated with one of said recorders for forming undulations in one of the records, and sound-sensitive electrically controlled means associated with the other of said recorders for forming undulations in the record associated therewith, said turntables being arranged to be moved in synchronism with respect to each other and in synchronism with said disc.

Signed at Chicago, in the county of Cook
and State of Illinois, this 7th day of August,

A. D. 1928.

CHARLES EMANUEL ALBERTI.
